SPRING GROUP ASSEMBLY

John E. Flesch, Los Angeles, Calif., assignor to
 American Steel Foundries, Chicago, Ill., a corporation of New Jersey

Application April 21, 1950, Serial No. 157,387

11 Claims. (Cl. 267—9)

1

This invention relates to a package spring group of the type commonly utilized to support a bolster from a side frame of a railway car truck.

A general object of the invention is to devise a spring package group comprising spaced plates with friction means for controlling movements of the package and wherein novel removable retaining means are incorporated to interlock the parts in operative assembly.

A further object of the invention is to provide simple, efficient locking or retainer means which will fit in the space limitations inherent in such package and which will perform efficiently in service.

Another object of the invention is to design an economical retainer means of rugged form which will withstand the severe abuse in service.

A different object of the invention is to design retainer means which are removable from the package only when the package is disassembled from its supported and supporting members, and only when the package is compressed.

A more specific object of the invention is to devise a retainer arrangement, wherein the retainer must be moved consecutively in several angularly related directions to disassemble from the cooperating parts.

These and other objects of the invention will become more apparent from the specification and the drawings, wherein:

Figure 1 is a top plan view of the package spring group, embodying the invention;

Figure 2 is an end elevational view of the group partly in section on the line 2—2 of Figure 1, the springs in the foreground being removed to clarify the view;

Figure 3 is a sectional view taken substantially on the line 3—3 of Figure 1; and

Figure 4 is a fragmentary sectional view taken substantially on the line 4—4 of Figure 2 and illustrating the application of a shim block to adjust the expansion of the group.

Describing the invention in detail, the novel package spring group comprises top and bottom spring plates, generally designated 2 and 4, having four spring units, each consisting of an outer coil spring 6 and an inner coil spring 8 compressed between the plates. Each of the plates is provided with cored openings 10 aligned with coil springs 8 and is provided with a plurality of positioning lugs 12, 12 adapted for reception within complementary openings of associated supported and supporting members such as a bolster and side frame, not shown, of a conventional railway car truck. In this connection it may be noted

that the group may be inverted with the plate 4 at the top and the plate 2 at the bottom.

The top plate 2 is provided with peripheral arcuate flanges 14 merging with lateral or side flanges 16, said flanges being adapted to afford positioning means for the springs 6 and 8. The top plate 2 also comprises an integral depending friction housing or top follower including spaced end walls 18 integrally formed with the flanges 16. Each of the end walls is formed with a pair of spaced ledges 20, 20 sloping downwardly and inwardly and adapted to afford wedge seats for an associated friction shoe, as hereinafter described. The end walls are connected by a pair of side walls 22, 22 which are bowed away from each other as at 24, 24 longitudinally of the group intermediate their ends and connected at their upper edges with the underside of the top plate 2. The lower edges of the side walls 22 are arcuately formed or cut out as at 28.

The bottom plate comprises a central friction post or column, generally indicated 30, which extends upwardly from the center of the bottom plate and telescopes into the housing or top follower. The friction post is substantially square in cross section and comprises opposed walls 32, 32 and opposed walls 33, 33 which define a central opening 34 within the post, the lower end of the opening 34 extending through the bottom plate 4. The opposite walls 32, 32 of the post extend generally parallel to the end walls 18, 18 of the casing and are provided with friction plates 36, 36 suitably connected thereto as by welding at 38.

A friction shoe, generally indicated at 40, is positioned at each end of the casing at opposite sides of the post 30, the shoe having a main or friction wall 42 engaging the related friction plate 36 and having a bottom or spring seat wall 44 and having a pair of spaced ledges 46, 46, each engaged with one of the ledges 20 of the related friction housing wall 18, the ledges being connected to a rear wall 47. A spring, diagrammatically indicated at 48, is housed within each shoe for urging the ledges 46 against the engaged ledges 20 and thereby urging the shoe along said ledges into frictional engagement with the related friction plate 36.

The plate 2 and the bottom shoe wall 44 are provided with registerable openings 50 and 52 respectively, adapted for reception of associated means such as a bolt and nut assembly (not shown) for retracting the shoes during assembly of the group, as hereinafter described.

The feature of the present invention is the provision of retaining means for limiting expansion

of and maintaining the spring group in assembled relationship, the retaining means comprising a bar or column 54 within the post 30 and the column or bar 56 connected to the top plate. The bar or stop members 54 and 56 are arranged parallel and the bar 56 is disposed directly above the bar 54. The bar 54 is located adjacent to the upper end of the friction post 30 centrally between walls 32, 32 parallel thereto and is formed at opposite ends integral with walls 33, 33 of the friction post. The bar 56 extends transversely of the walls 22, 22 of the casing or top follower and at opposite ends is formed integral with the walls 22 and at its top side adjacent each end is formed integral with the underside of the top plate 2. The intermediate portion of the bar 56 extends below an opening 58 formed centrally through the top plate 2. The top plate is reinforced by a depending boss 60 formed around the margins of the opening 58.

A lengthwise vertically extending C-shaped retaining member, generally indicated 62, is disposed between the shoes 40, 40. The retaining member 62 comprises a shank 64 intermediate its ends, said shank extending at its lower end into the upper end of the opening 34 in the friction post 30 and having a hook portion 66 at its lower end hooked under the bar 54. It will be noted that the shank 64 extends between the bar 54 and adjacent wall 32 and is spaced transversely inwardly of the latter. The upper end of the shank 64 of the retainer member 62 is also provided with a hook 68, the hook 68 passing over the bar 56. It will be noted that the upper end of the shank and adjacent portion of the hook 68 is spaced from the adjacent side of the opening 58. It will also be noted that the hook portions 66 and 68 engage the bar 54 as at 70 and the bar 56 as at 72 respectively, along complementary curved surfaces, whereby the hook portions 66 and 68 have rockable engagement with bars 54 and 56 on axes extending substantially parallel to the generally vertical friction plates 36, 36 thereby accommodating, without binding, lateral shifting between the top and bottom plates 45 against the action of the friction means. It will be noted that if desired the surfaces at 70 and 72 of the hook portions 66 and 68 may also be curved longitudinally of the spring group. It will be obvious, however, that longitudinal lateral 50 and torsional movement between the top and bottom plates is normally not restricted by the retainer inasmuch as the spring group is normally compressed and hook portion 66 is disengaged from the bar 54 when such movements take place. It will be noted that the upper end of the hook portion 68 affords a seat at its upper side as at 74 for an associated supported or supporting member such as a bolster or side frame of a railway car truck, the surface at 74 being co-planar with the exterior seat surface 75 of the top plate 2.

The bottom plate is provided with arcuate up-standing end flanges 76, 76 merging with lateral flanges 78, 78, said flanges 76 and 78 affording positioning means for the spring units 6, 8. The bottom plate is offset upwardly at its lateral edges to provide pockets as at 80, 80 whereby the bottom plate is adapted to fit on a side frame of a double truss type as will be readily understood by those skilled in the art, the pockets 80, 80 receiving the secondary trusses of such a side frame.

In assembling the novel unit the springs 48 are inserted into the friction shoes 40 and the latter 75

are seated against the friction housing ledges 20 and retracted toward the plate 2 as by nut and bolt assemblies (not shown) extending through the openings 50 and 52 to retain the shoes in their innermost retracted position within the friction housing or top follower. The springs 6 and 8 are then inserted between the plates 2 and 4 which are seated thereagainst. Then the spring package is compressed. Then the retainer 62 is positioned flatwise parallel to the bars or lugs 56 and 54 and inserted into position through opening 53 between one side thereof and the adjacent side of bar 56, the retainer being lowered until the bottom hook portion 66 is disposed below the bar 54. Then the retainer is turned a quarter of a turn or 90 degrees so that it is positioned flatwise substantially perpendicular to the bars 56 and 54. The retainer is then lowered and the hook portion 68 is engaged as at 72 with the top side of the bar 56. It will be understood that the lower hook portion 66 will thus automatically assume a position directly beneath the bar 54. It will be noted that the retainer is prevented from rotating parallel to the bars 54 and 56 because of its engagement as at 74 with a member seated on seat 75. It will be noted that the hook portion 66 is wider than the spaces between the bar 54 and either wall 32. Similarly, the hook portion 68 is wider than the spaces at opposite sides of the bar 56 and the adjacent sides of the opening 58. This arrangement maintains the hook portion 66 at least partially in vertical alignment, whereby, when the spring group is expanded, as shown in Figures 3 and 4, the hook portion 66 will receive the bar 54 within its throat 82. It will be understood that preferably the upper and lower hook portions are the same and that the manner of identifying as heretofore is merely to clarify the description.

It will be understood that in order to disassemble the spring group, the spring group is partially compressed. The retainer is then lifted until the upper hook 68 clears the bar 56 that is, the bar is completely withdrawn from the throat 84 in the hook portion 68. It will be understood that the spring group is sufficiently compressed so that, when the retainer is lifted as just described, the lower hook portion 66 is disengaged from the bar 54 and the bar 56 is completely out of the throat 82. The retainer is then turned so that its major plane is parallel to the bars 54 and 56. The retainer may then be withdrawn through the opening 54. It will be understood that the retainer 62 may be assembled or disassembled with the top and bottom plates through the lower end of opening 34.

It will be readily appreciated that, if initial pre-compression is desired, a shim block 86 may be disposed between bar 54 and the associated hook portion 66 within the throat thereof. The block 86 may be of nonferrous metal such as aluminum whereby it will be quickly disintegrated by the pounding between the bar and hook portion after few compressions and expansions of the spring group.

I claim:

1. A package spring group comprising spaced top and bottom spring plates, a plurality of springs therebetween, a hollow friction post connected to said bottom plate and extending upwardly therefrom, a transverse bar within the upper end of the post connected thereto, a bar on said top plate above said first-mentioned bar and parallel therewith, said top plate having an opening therethrough above the bar thereon, and

means for limiting expansion of said group comprising a retainer member extending from one bar to the other along one side thereof and having a hook portion hooked over the bar on the top plate and having another hook portion hooked under the bar in the post, said retainer being spaced from the sides of the opening and said post and said hook portions engaging respective bars along complementary curved surfaces concentric with the axes of said bars whereby said top and bottom plates are relatively movable transversely and torsionally of said bars in the expanded condition of said group without interference by said retainer member, said retainer member extending upwardly in said opening and having a top end surface substantially coplanar with the top side of said plate whereby said retainer member is held tightly in position by an associated member seated thereon, said retainer member being wider than the space between the bar in said post and the adjacent side of the post whereby said retainer member is prevented from canting to a position whereby said other hook portion is always disposed in at least partial vertical alignment with the bar in the post.

2. In a spring group, top and bottom plates, a housing on one plate, a hollow friction post on the other plate telescoping into said housing, friction means carried by said housing at opposite sides of the post in frictional engagement therewith, said one plate having an opening therethrough aligned vertically with the space within said post, a tie bar within said post at the end thereof adjacent to said one plate, a tie bar on the inside of said one plate extending across said opening, and a retainer member extending between said plates along a side of said bars and having hook portions hooked around the remote sides of said bars in the expanded condition of said group, said bars at said one side being spaced from the adjacent side of the post and opening a sufficient distance to admit either hook portion therethrough when the same is positioned flatwise substantially parallel to the bars.

3. A spring group comprising top and bottom plates, springs therebetween, a hollow post on said bottom plate, a tie bar within the post and a tie bar on said top plate, said top plate having an opening therethrough above the tie bar thereon, a retainer extending lengthwise between the plates and extending edgewise transversely of the bars in the assembled position therewith and having spaced hook portions extending around the remote sides of said tie bars, said retainer being thinner than the space between the bar on the plate and the adjacent side of the opening and between the bar on the post and adjacent side of the post, said retainer being rotatable when said hook portions are disengaged from said bars to a position flatwise parallel to said bars whereby said retainer may be withdrawn from said post and opening for disassembly.

4. In a spring group, spaced plates, resilient means confined therebetween and means for limiting the expansion of said group comprising a removable retainer extending between said plates and comprising an element hooked at one end to one of said plates and extending through an opening therein, said element and said one plate presenting seating surfaces for an associated member, and a hook portion on the other end of said element arranged to hook behind a portion of the other of said plates, said element being adapted to tightly engage with said one

plate when said member is seated on said surfaces whereby said element is maintained in position to engage behind said portion of the other plate when said group is expanded.

5. In a spring group, top and bottom plates, retainer means connected between said plates for limiting expansion of the group, said retainer means having a connection at one end with one plate, and a lost-motion connection between the other end of the retainer means and the other plate, said lost-motion connection comprising an anchor on the other plate and a hook on said retainer means disposed in assembled condition with the anchor around a side of the anchor remote from the one plate and extending edgewise transversely of said anchor when in assembled condition therewith, said retainer means being movable to a position disposing said hook portion flatwise along a side of said anchor to accommodate assembly and disassembly of said retainer means with respect to said anchor.

6. A package spring group comprising top and bottom plates, spring means therebetween, anchor means on the adjacent sides of said plates, and removable retainer means extending from the anchor means on one plate to the anchor means on the other plate and hooked around the remote sides of said anchor means in the expanded condition of said group, said retainer means being disengageable from the anchor means on one of said plates when said spring means are compressed causing said plates to be advanced toward each other, and means on said one plate for guiding said retainer means in a path engaging said retainer means with the anchor means on the one plate when said package is expanded.

7. A package spring group comprising spaced plates, springs therebetween, a hollow post on one plate, and retainer means between said plates for limiting expansion of the group, said retainer means comprising a C-shaped member extending into said post at one end and into an opening in the other of said plates at the other end, and abutment means in the post and on said other plate beneath the opening therein extending through said C-shaped member for abutment with respective ends thereof, said post guiding the movement of said member to maintain the portion thereof engageable with said abutment means in the post in substantial alignment therewith longitudinally of the post.

8. In a spring group, spaced plates, springs compressed therebetween, and retainer means between the plates for limiting expansion of the group and comprising a C-shaped member hooked at opposite ends to the respective plates, guide means on at least one of said plates for guiding said member during relative movement of said plates to maintain said member in hooking position with the associated plate, and means on one of said plates accommodating disassembly of said retainer means only upon compression of said group.

9. In a spring group, top and bottom plates, a hollow post on one of said plates extending toward the other, and means for limiting expansion of said group removably connected to said post and other plate and comprising tie bars in said post and on said other plate, said other plate having an opening therethrough in alignment with the bar thereon, and a retainer hooked around the remote sides of said bars.

10. In a spring group, top and bottom plates, spring means therebetween, anchor means on respective plates, and a C-shaped retainer hooked

around said anchor means to limit expansion of the group, and means for adjusting the expansion of the group interposed between a side of the anchor means on one plate remote from the other and an adjacent portion of the retainer.

11. A package spring group comprising spaced spring plates, a plurality of springs confined therebetween, a hollow member carried by one plate, a transverse bar within said member, a retainer removably connected to the other plate at 10 one end and having a hook portion at the other

end extending into said member and juxtaposed in hooking relationship to said bar.

JOHN E. FLESCH.
